UNITED STATES PATENT OFFICE.

LOUIS H. TOLHURST, OF LOS ANGELES, CALIFORNIA.

FIBER-ROLLING MACHINE.

1,333,230.

Specification of Letters Patent.

Patented Mar. 9, 1920.

Application filed June 24, 1918. Serial No. 241,698.

To all whom it may concern:

Be it known that I, LOUIS H. TOLHURST, a citizen of the United States, residing at Los Angeles, in the county of Los Angeles and State of California, have invented a new and useful Fiber-Rolling Machine, of which the following is a specification.

My invention relates to the art of preparing vegetable fiber, and more particularly to the art of separating such fiber from the woody pulp with which it is found associated in nature. The invention is particularly applicable to the separation of vegetable fiber from the leaves of the yucca or Spanish bayonet. In this plant the leaves are made up of parallel fibers incased in woody material, and it is necessary to free the fibers from the material in which they are embedded if the fiber is to be used commercially in the production of rope, binder twine and the like to which such fiber is particularly applicable.

Other objects and advantages will be made evident hereinafter from the following specification.

Referring to the drawings, which are for illustrative purposes only,

Figure 1 is a side view of a machine embodying my invention.

Fig. 2 is a section on a plane represented by the line 2-2, Fig. 1, and viewed in the direction of the arrow of that figure.

Fig. 3 is a plan view of my invention, and

Fig. 4 is a section on a plane represented by the line 4-4 of Fig. 3, and viewed in the direction of the arrow of that figure.

In the embodiment of my invention illustrated in these drawings, a wooden frame 11 is provided. Turning in suitable bearings 40 which are rigidly secured to the frame are shafts carrying a head pulley 12 and a tail pulley 13. Also carried in blocks 14 sliding in the frame 11 is a shaft carrying a belt adjusting roller 15, each of the blocks 14 being adjustable up and down by means of a screw 16. Rollers having fixed axes are placed at 17, 18, 19 and 20, the rollers 17, 18 and 20 being directly below movable rollers 21, 22 and 23. These movable rollers are 50 mounted on shafts turning in bearings carried in blocks 24 which are vertically movable in the frame 11 against compression springs 26, the pressure of each of the springs 26 being adjusted by a screw 25. A 55 flexible belt 30 passes around the pulleys 12,

13, 15 and 19, this belt also passing between the rollers 17 and 21 and rollers 18 and 22.

The shafts to which the rollers 21 and 22 are fixed are provided with sprockets 31 and 32 which are connected by a chain 33. The 60 shaft to which the roller 21 is fixed is driven through a gear train 34 from a main shaft 42 which is equipped with a driving pulley 43 on which a suitable belt may be placed for driving the machine from any suitable 65 source of power. The shafts to which the rollers 18 and 22 are secured are connected by means of gears 45, and the shafts on which the rollers 20 and 23 are secured are connected by means of gears 46, the gears 70 46 being driven from the gears 45 by means of an idler gear 47 which turns freely on the shaft of the roller 19, and in an opposite direction to the rotation of that roller.

Mounted on the shaft 42 is an eccentric 50 75 having an eccentric strap 51 to which a connecting rod 52 is secured, this connecting rod being pivoted on a pin 53 pivoted in a block 54 which forms a portion of a carriage 55. Mounted so as to turn freely in this carriage is a plurality of upper rollers 56 and lower rollers 57, each of the upper rollers 56 being on the upper side of the belt 30 and directly above a co-acting lower roller 57. The rollers 56 are mounted on shafts which 85 turn in blocks 58 which are free to move vertically in guides 59, each of the rollers 56 being, however, held down with considerable pressure by means of springs 60 which press upon the blocks 58 and tend to 90 force the rollers 56 and 57 together. The rollers 56 and 57 are forced together subject to the tension of the springs 60 by means of screws 61 operated by hand wheels 62. The carriage 55 is provided with trunnion 95 wheels 70 so that it rests upon the side frame 71 of the frame 11. Spray pipes 80, perforated with a multiplicity of small holes 81, are placed between the rollers 56 and secured to the carriage 55, being supplied with 100 water through a flexible pipe 82, the water being caught in a tank 83 from which it may be recirculated to the pipe 82 by a pump 84.

The method of operation of my invention 105 is as follows:

The shaft 42 being driven by means of the pulley 43 from any source of power (not shown), the belt 30 is driven at the rate of about three feet a minute in the direction 110

of the arrows shown in Figs. 1, 3 and 4 through the gearing 40 and through the chain 33 and the gearing 34, the belt being gripped between the rollers 17 and 21, and between the rollers 18 and 22. The partially disintegrated leaves of the yucca, which have previously been boiled or otherwise treated to partially disintegrate them, are placed on the top of the belt 30, being carried in the direction of the arrow between the rollers 17 and 21. The tension of the springs 60 forces the rollers 21 and 17 together so that the yucca is partially crushed and flattened out on the belt to which it adheres more or less due to this crushing. In this partially flattened and crushed condition it passes between the rollers 56 and 57. The carriage 55 in which these rollers are journaled is reciprocated by means of the eccentric 50 which drives the eccentric strap 51 and through the connection rod 52 drives the frame 55.

As the yucca passes forward on the belt the rollers 56 are passed forward and back over the yucca pressing it against the belt which is sustained on the rollers 57. In practice the shaft 42 is rotated at about sixty revolutions per minute. By means of the movement of the rollers back and forth the effect of a long belt with a large number of rollers is obtained. It is necessary that the yucca fiber be delivered from the machine in a fairly straight and parallel condition so that it will not become tangled and so that its subsequent use will be facilitated. By running the belt 30 at a low speed and by moving the rollers 56 and 57 rapidly it is possible to roll out the yucca leaves very thin without danger of tangling or snarling the separate fibers. The addition of water through the pipes 80 facilitates the separation and in some cases certain other solvents may be so supplied in the place of water. The solvent is caught in the tank 83 and recirculated if desired.

I have found that by supplying plenty of water and maintaining the material under considerable pressure that I am able to separate from the partially disintegrated mass nearly all of the undesirable material, so that the material passing between the rollers 18 and 22 consists of as high as ninety-eight per cent. fiber, the cellular and pectinous material having been washed out of the mass by the action of the water and the pressure of the rolling operation. The cleaned fiber

passes up the inclined belt which serves to partially drain the fiber and between the rollers 18 and 22, which serve to wring a large portion of the water out of the fiber, 60 the rollers 20 and 23 serving to further wring out water from the fiber.

The final product is in the form of fiber which is fairly parallel and straight, and which is almost entirely separated from the 65 pulp. This fiber after being dried may be used in the production of rope, binder twine, or the like, and forms a valuable commercial product.

What I claim is:—

70

1. A fiber rolling machine comprising a belt on which a mass of vegetable matter containing the desired fiber is carried; means for supporting said belt; a series of upper rollers pressing on the mass on said 75 belt; belt driving means for driving the belt; and roller reciprocating means for forcing the rollers to travel back and forth on said belt.

2. A machine as in claim 1 in which the 80 means for supporting said belt comprises a series of lower rollers each of said lower rollers being placed directly below one of said upper rollers and so supported that it reciprocates in fixed relationship with said 85 co-acting upper roller.

3. A fiber rolling machine comprising a frame; belt rollers turning in bearings fixed to said frame; a belt passing over said rollers; driving means for said belt; a carriage; 90 friction reducing means for supporting said carriage on said frame in such a manner that said carriage can be reciprocated with relation to said frame; means for so reciprocating said carriage; an upper roller 95 turning in bearings in said carriage and located above said belt; a lower roller turning in bearings in said carriage and located below said belt; and pressure means for elastically forcing said upper and lower rollers 100 together.

4. In a fiber rolling machine, a belt on which the fiber is carried, upper and lower rolls between which said belt passes, means for moving said rolls back and forth on said 105 belt, and means for moving the belt through said rollers.

In testimony whereof I have hereunto set my hand at Los Angeles, California, this 15th day of June, 1918.

LOUIS H. TOLHURST.
